APPARATUS FOR OBTAINING HYDROGEN PEROXIDE BY DISTILLATION

Josef Müller, Weissenstein ob der Drau, Austria

Application December 19, 1929, Serial No. 415,368,
and in Germany January 3, 1929

8 Claims. (Cl. 202—52)

The invention relates to the production of hydrogen peroxide from solutions containing or yielding the same, such as solutions of persulphuric acid or solutions of persulphates.

5 It is already known to submit such solutions to distillation while flowing in a thin film of large area which is heated to effect rapid evaporation. A process of this kind is described in the patent to Löwenstein No. 1,013,791 which accord-

10 ing to the example shown in this specification is carried out in such a manner, that the solution to be treated is admitted at the top of a vertical externally heated distilling tube so as to run downwards over the interior surface of the wall 15 of the tube, while the hydrogen peroxide vapors distilled off are discharged at the upper end of the tube. Consequently the liquid and the hydrogen peroxide vapors are moving in counter-current.

20 For the construction of the distilling tubes ceramic material was almost exclusively at the disposal of the practical work, in spite of many attempts for replacing this fragile material, the heat conductivity of which is very low, by a metallic material which would be more fitted for 25 the purpose. On account of the high costs of precious metals the endeavours were especially directed towards finding out ordinary metallic materials sufficiently resistant to the several reaction components.

30 In the patent to Levin and Molin No. 1,323,075 it has been proposed to render possible the use of lead for the construction of such heated distilling tubes by a special way of carrying out 35 the distilling process which was based on the assumption that any chemical action between the heated walls of the distilling tube and the hydrogen peroxide vapors could be avoided, if the vapors are removed and condensed as promptly 40 as possible after generation. For this purpose a thin walled lead tube has been used to ensure a rapid transfer of heat, in which tube the persulphuric liquid to be treated is introduced at the top, while the peroxide vapors distilled off pass 45 upwardly in counter-current to the downward streaming liquid.

50 Later on it has been proposed to use tantalum for the purpose in question. On the other hand also the use of chromium steels (chromium nickel alloys) has been suggested. But there exists up to now no possibility of making distilling tubes of tantalum at fairly reasonable costs, and also the use of chromium steels has not been successful in practice.

55 I have now found that tubes of relatively great

length can be employed for carrying out distillation processes of this kind without, as might have been feared, the hydrogen peroxide becoming decomposed to any detrimental extent, even if the tubes of such length are made of lead or like ordinary metal. Thus for instance a length of more than 10 meters may be chosen, advantageously one more than 30 meters. Excellent results have been obtained by using tubes having a length of 50 to 75 meters.

60 Lead decomposes persulphuric liquid and is attacked by persulphuric solutions which on heating yield hydrogen peroxide and sulphuric acid, permonosulphuric acid being produced as an intermediate product; but this is only the case on the condition that hydrogen peroxide is already contained in the heated persulphuric liquid. On the other hand lead has been found to be perfectly inert (even when the solutions are heated) to persulphuric acid and permonosulphuric acid 75 solutions free of hydrogen peroxide, consequently also to the residual liquor which is produced in the preparation of hydrogen peroxide by distillation of persulphuric solutions, provided said residual liquor is free of hydrogen peroxide.

80 Now in the distillation of the persulphuric liquid prepared for the purpose of recovering hydrogen peroxide therefrom first of all the persulphuric acid is transformed into monopersulphuric acid without any hydrogen peroxide being 85 generated meanwhile. Consequently lead is perfectly inert to the acids in question in the first section of the distilling tube. Only when nearly the whole persulphuric acid has been converted into monopersulphuric acid, the generation of 90 hydrogen peroxide will set in. In this moment, however, there is with distilling tubes of suitable dimensions already such a high speed of the vapours attained (e. g. 100 meter per second increasing up to 300 m/sec.), that a mutual chemical action between the wall of the lead tube and the hydrogen peroxide vapors is avoided, the more so as the wall is also protected by an outermost thin layer of the persulphuric liquid streaming along the heated wall, which outermost layer 95 forms a covering film of mother liquid perfectly freed from hydrogen peroxide.

100 The velocity of flow is inversely proportionate to the cross-section of the distilling tube, that is to say, it diminishes in direct proportion with the increase of the sectional area of the distilling tube. On the other hand the speed increases proportionally with the throughput (amount of charge per unit of time). Consequently the lower streaming velocity in tubes having a larger 110

sectional area may be balanced by increasing the throughput. The throughput on its part is limited by the length of the tube, since in tubes being not long enough the hydrogen peroxide vapors formed by hydrolysis are not completely driven out of the liquid under treatment.

As is seen therefrom, the speed can be adjusted at will within certain limits by the choice of an appropriate relation between the length and the sectional area of the tube, so that any decomposition of the hydrogen peroxide can be avoided even if distilling tubes of considerable length are employed.

Moreover I have found that advantageously spiral tubes can be used as distillation apparatus, as they can be disposed in a small space and be uniformly heated in a simple manner.

The tubes may for instance be made of metallic material highly resistant to acids and to the action of active oxygen (e. g. gold or platinum) or inside plated therewith. But most advantageously lead or lead alloys are used for this purpose (in the one or the other of these ways).

It has for instance been found advantageous, if for a length of the pipe amounting to 60 meters an internal diameter of 75 millimeters is chosen.

In the following an example of carrying the invention into practice is given, reference being made to the annexed drawing which shows a partly sectional elevation of a distillation apparatus.

Within a steam jacket 1 a distilling tube wound in the form of a spiral or, as shown, in that of a helical coil 2 is enclosed, the two ends of which pass through stuffing boxes 3 provided on the jacket. This coil consists for instance of a thick walled lead tube 75 millimeters wide and 60 meters in length, which is wound into a coil about 10 to 25 turns or windings. Steam can be admitted through the pipe 4 and the water resulting from condensation drawn off through the pipe 4'. The acid to be treated is supplied at the top of the coil to flow downwards.

About 200 to 250 liters per hour of sulphuric acid containing persulphuric acid (25% $H_2S_2O_8$) are passed through this coil in the downward direction. The vacuum amounts to about 650 to 700 millimeters. The hydrogen peroxide given off may be recovered in suitable condensers, if necessary, by means of fractional condensation.

By the invention the obtaining of high yields of hydrogen peroxide from solutions of persulphuric acid or the like by means of a very simple apparatus is rendered possible, which apparatus can very easily be operated. The consumption of steam which in the commercial production of hydrogen peroxide by distillation is of great importance, is relatively very small.

I claim:—

1. A process for obtaining hydrogen peroxide by distillation of solutions capable of liberating it, which consists in passing the solution and the liberated hydrogen peroxide vapors in the same direction through a heated ascending distilling tube of more than ten meters in length, the liquid to be distilled being admitted at the top of the said distilling tube to flow downwards.

2. A process for obtaining hydrogen peroxide

by distillation of solutions capable of liberating it, which consists in passing the solution and the liberated hydrogen peroxide vapors in the same direction through an externally heated ascending distilling tube of more than ten meters in length, the liquid to be distilled being admitted at the top of the said distilling tube to flow downwards.

3. A process for obtaining hydrogen peroxide by distillation of solutions capable of liberating it, which consists in passing the solution and the liberated hydrogen peroxide vapors in the same direction through an externally heated distilling tube formed into a coil of a length of more than ten meters, the liquid to be distilled being admitted at the top of the said coil to flow downwards.

4. A process for obtaining hydrogen peroxide by distillation of solutions capable of liberating it, which consists in passing the solution and the liberated hydrogen peroxide vapors in the same direction through an externally heated distilling tube formed into a helical coil of more than ten meters in length, the liquid to be distilled being admitted at the top of the said distilling tube to flow downwards.

5. A process for obtaining hydrogen peroxide by distillation of solutions capable of liberating it, which consists in passing the solution and the liberated hydrogen peroxide vapors in the same direction through an externally heated ascending distilling tube of more than ten meters in length which offers to the solution an internal surface consisting of a metallic material resistant to the residual liquor freed from hydrogen peroxide, the liquid to be distilled being admitted at the top of the said distilling tube to flow downwards.

6. A process for obtaining hydrogen peroxide by distillation of solutions capable of liberating it, which consists in passing the solution and the liberated hydrogen peroxide vapors in the same direction through an externally heated ascending distilling tube of more than ten meters in length, this tube being made from lead, the liquid to be distilled being admitted at the top of the said distilling tube to flow downwards.

7. A process for obtaining hydrogen peroxide by distillation of solutions capable of liberating it, which consists in passing the solution and the liberated hydrogen peroxide vapors in the same direction through an externally heated coiled distilling tube of a length amounting to 60 meters and having an internal diameter of 75 millimeters, the liquid to be distilled being admitted at the top of the said distilling tube to flow downwards.

8. A process for obtaining hydrogen peroxide by distillation of solutions capable of liberating it, which consists in passing the solution and the liberated hydrogen peroxide vapors in the same direction through a heated coiled distilling tube of more than ten meters in length while lowering the distillation temperature by applying a vacuum, the liquid to be distilled being admitted at the top of the said distilling tube to flow downwards.

JOSEF MÜLLER.
